UNITED STATES PATENT OFFICE.

PETER DOSCH AND CHARLES R. DOSCH, OF STRATFORD, CONNECTICUT.

DISK-GRINDING MACHINE.

1,193,525.

Specification of Letters Patent.

Patented Aug. 8, 1916.

Application filed January 26, 1916. Serial No. 74,327.

To all whom it may concern:

Be it known that we, PETER DOSCH and CHARLES R. DOSCH, both citizens of the United States, residing at the town of Stratford, county of Fairfield, State of Connecticut, have invented certain new and useful Improvements in Disk-Grinding Machines; and we do declare the following to be a full, clear, and exact description of the invention, 10 such as will enable others skilled in the art to which it appertains to make and use the same.

This invention relates to certain new and useful improvements in a disk grinding machine and particularly to that type of machine embodying a grinding disk, a dust collector and an adjustable work table.

An important object resides in the novel mounting of the disk on the motor shaft 20 whereby the former is easily removable from the shaft and is adapted to be firmly attached without interrupting the abrading surface as by screws or bolts employed in attaching the disk.

25 A further object is to provide a dust collector which will house the lower portion of the grinding disk and also constitute a support for the work table.

Another aim resides in mounting or supporting the work table so that it may be 30 swung or adjusted vertically with its inner edge always close to the grinding disk.

The invention further resides in the features of construction, arrangements and 35 combinations of parts hereinafter described and claimed, reference being had to the accompanying drawings wherein:

Figure 1 shows the preferred form of the invention in top plan; Fig. 2 illustrates the 40 same in front elevation; Fig. 3 is a side elevation of the machine showing in dotted line an adjustment which the table is capable of making; Fig. 4 is a vertical section through the dust collector taken along line 45 4—4 of Fig. 3; Fig. 5 is a vertical section through the grinding disk and its mounting; and Fig. 6 is a rear view of the cheek plate to which the grinding disk is attached.

Referring more in detail to the drawings, 50 the dust collector 1 is suspended from the base 2 of a motor 3 which latter is preferably electrical.

The shaft 4 of the motor has fixed to one 55 end the hub 5 of a cheek plate 6 which latter is formed with a concentric series of key-hole-shaped openings each consisting of

an entrance or escape portion 7 and a restricted slot portion 8.

The grinding disk 9 has its active face 10, 60 preferably in the form of sand paper or emery cloth, adhesively or otherwise secured thereto, while to the rear face and extending axially therefrom are a series of threaded pins 11 carrying nuts 12. These nuts, which have broad, washer-like, bearing faces 12', 65 are of sufficient size to pass through the entrance openings 7 and, when the pins are moved into the slots 8 by rotating the disk 9 on the cheek plate 6, to clamp the rear face of the latter to secure the disk to the 70 plate.

The rear face of the disk 9 is centrally recessed to receive a hub extension 13 which further aids in supporting and centering 75 the disk.

The dust collector houses the lower portion of the grinding disk and has its opposite sides formed with arcuate channels or recesses 14 in which operate inwardly extending ribs 15' of the similarly shaped 80 brackets 15. These brackets support the work table 16 so that the forward edge of the latter is at the center about which the arc shaped brackets swing. By this mounting, the inner edge of the table is always 85 close to the grinding disk, the distance being the same throughout all adjustments, as depicted in Fig. 3.

A clamping rod 17 extends through the 90 collector 1 and has on one end a permanent head or jaw 18 overlying one of the brackets 15. The opposite end of rod 17 is threaded to receive a nut member 19 which bears on a slidable jaw 20 and, when tightened, clamps the jaws 18 and 20 against 95 their respective brackets, as clearly disclosed in Fig. 4. The jaw 20 is conveniently provided with a setting mark adapted to register with the scale on a bracket 15, Fig. 3, whereby the desired inclination of the table 100 105 may be accurately obtained.

In order to provide ample room to remove the grinding disk, the table is provided with a detachable forward section 21 which is secured in position by a screw 22. By thus removing this table section, sufficient space is provided for the axial movement required in removing the disk.

A work guide 23 is pivoted to a block 24 110 for angular adjustment which is slidable in a transverse groove 25 provided in the table. This enables the operator to take advantage

of the full width of the disk by permitting of his sliding his work across the table and thus not wear the grinding surface at any particular place.

5. The practical and compact arrangement of the various parts of the machine will be evident from the foregoing, it being noted that the work table is supported entirely from the dust collector.

10. What is claimed is:

1. In a grinding machine, a grinding disk, a dust collector therebeneath, and a work table adjustably supported on the collector and covering the latter.

15. 2. In a grinding machine, a grinding disk, a dust collector arranged therebeneath and partly receiving the disk, a work table, and arc-shaped brackets adjustably supporting the table from and above the collector to constitute a guard and closure for the latter.

20. 3. In a grinding machine, a grinding disk, a dust collector arranged therebeneath and having its opposite sides provided with arcuate channels, a work table, and arcuate brackets adjustably engaged in the channels of the collector for supporting the table.

25. 4. In a grinding machine, a grinding disk, a dust collector arranged therebeneath and having its opposite sides provided with arcuate channels, a work table, arcuate brackets slidable in the channels of the collector and supporting the table, and clamp means carried by the collector for engaging with and adjustably securing the brackets.

30. 5. In a grinding machine, a grinding disk, a dust collector arranged therebeneath and partly receiving the disk, said collector having its opposite sides between which the disk is disposed provided with arcuate channels, a work table, arcuate brackets slidable in the channels of the collector and supporting the table with its forward edge sub-

stantially at a fixed point above the dust collector to always overlie the latter.

45. 6. In a grinding machine, a rotatable support, a grinding disk thereon, removable by axial movement, and a sectional work table arranged across and adjacent to the disk and having that section nearer the disk movable from an operative position to provide ample room for the removal of the disk.

50. 7. In a grinding machine, a rotatable support, a grinding disk removably secured thereto, a work table, means for supporting the table for arcuate movement transversely of the disk, and a forward removable section of the table adjacent the disk, whereby on the removal of said section space is provided for the removal of the disk, said 55 means supporting the table so that the edge of the forward removable section, when the latter is in an operative position, is substantially in a fixed point.

55. 8. A grinding machine comprising an abrading element, a motor for rotating the element, a base plate supporting the motor and extending forwardly thereof, an elongated transversely arranged dust collector carried at the forward edge of the base 70 plate and depending therefrom, the opposite ends of the collector being formed with curved seats, a work table, brackets engaged in the seats of the collector and supporting the table, and a clamping device arranged on 75 the collector adjacent a seat thereof to impinge on the adjacent bracket to hold the table fixed.

In testimony whereof we affix our signatures in presence of two witnesses.

PETER DOSCH.
CHARLES R. DOSCH.
